UNITED STATES PATENT OFFICE.

GEORGE W. MILLER, OF WOONSOCKET, RHODE ISLAND.

MERCERIZING APPARATUS.

SPECIFICATION forming part of Letters Patent No. 628,669, dated July 11, 1899.

Application filed December 28, 1898. Serial No. 700,548. (No model.)

To all whom it may concern:

Be it known that I, GEORGE W. MILLER, a citizen of the United States, residing in the city and county of Woonsocket, in the State of Rhode Island, have invented certain new and useful Improvements in Apparatus for Supporting Skeins in Dyeing, &c., of which the following is a specification.

My invention relates to that class of apparatus used for supporting hanks or skeins of yarn in dyeing, mercerizing, &c.; and my invention consists of certain devices whereby to facilitate the operations upon such materials, as fully set forth hereinafter and as illustrated in the accompanying drawings, in which—

Figure 1 is a side elevation of an apparatus embodying my improvement; Fig. 2, an end elevation; Fig. 3, an enlarged view in part section; Fig. 4, a view showing a modification.

There are two supporting heads or frames A A' for the hanks or skeins of yarn or other material to be dyed, mercerized, or otherwise treated, and there are two or more tanks F G, above which the said supporting-heads are suspended in such manner that either head may be carried above either of the tanks and then lowered therein for any desired length of time and then again elevated, preferably being so counterbalanced that these operations may be performed with the exercise of but little labor upon the part of the attendant. As shown, both heads are supported by a revolving shaft E, having at the upper end a cross-arm H, carrying two pairs of pulleys 14 15 15, over which pass cables 13, arranged in pairs, as shown, one end of each cable being connected to the upper bar B of the supporting-frame A and the other end of the cables being attached to the upper bar B' of the supporting-frame A', whereby the two frames counterbalance each other, the inner ends of the bars B B' being recessed to receive the shaft E, which serves as a guide in the vertical movements of the supporting-frame.

At the lower ends of the supporting-frames are cross-bars D D', in which turn freely smooth-faced pins 1, projecting from the opposite sides of said bars, said pins 1 corresponding to similar pins 2, projecting from the upper bars B B', upon which pins are placed the hanks or skeins of yarn, &c., to be treated. The pins 2 of the upper bars are rotated by

any suitable means, so as to permit all parts of the material to be introduced into the fluid in the tanks, which can be done by rotating 55 the pins and causing the hanks or skeins of yarn to change their positions.

Suitable means may be employed for rotating the upper pins 2. As shown in Fig. 4, the pins are geared together by means of gears 3, 60 meshing with each other and combined with suitable means for rotating them—as, for instance, with a pinion 4 upon a worm-wheel 19, turned by means of a worm 6 on a shaft 7, provided with a hand-wheel 8. 65

It is necessary to set the cross-bars B B' at proper distances from the cross-bars D D', according to the length of the hanks or skeins, and also to stretch the same to prevent shrinking during mercerizing or dyeing, and I therefore make the cross-bars B B' adjustable with respect to the cross-bars D D'. This may be done by suitable appliances; but, as shown, connecting-rods 9, attached to the lower bars, are threaded at their upper ends, extend 75 through the upper bars, and receive nuts 10 10, which are the hubs of gears 20 20, turning on the upper cross-bars B B' and meshing with a pinion 21, connected with a hand-wheel 12 upon a shaft 16, which turns in the frame and 80 on which turns a ratchet-disk 17. A pawl 18, with a beveled lower end, engages the notches 22 in the disk 17, and from the latter extends a handle 16'. By vibrating the handle and disk 17 the pinion 21 can be turned intermittently to turn the gears 20 20 and apply any necessary power to tighten the hanks upon the pins 1 2. By turning the hand-wheel the nuts are rotated, thereby carrying the cross-bar B up or down upon the rods 9 9. 90

After the material carried by one of the supporting-heads has been introduced into one of the tanks and operated upon by the liquid therein the carrying-head may be elevated and then turned to a position above 95 another tank and be again immersed, and where there are more than two tanks this may be repeated with the different tanks. As a general thing, in the tank into which the material is last inserted is water, where it is 100 washed prior to being removed from the supporting-heads.

It will be obvious that while I have shown the carrying-heads A A' supported by a shaft

E they may be otherwise supported, so as to be moved into and out of tanks beneath the same, and instead of revolving they may be carried from one tank to another in a straight line.

In Fig. 3 I show means for applying power to turn the pins 2. In such case there is a toothed wheel 30, fixed on the shaft of the hand-wheel 8 and meshing with a pinion 31, on a vertical shaft 32, turning in a bracket P, secured to one end of the cross-bar. At the lower end of the shaft 32 is a bevel-gear 33, which when the bar B is lowered meshes with a bevel-gear 34 on a horizontal shaft 35, turning in bearings of a bracket 36, secured to the tank G and driven from any suitable source of power, so long as the bar B is in its lower position and it is necessary to turn the pins to impart travel to the yarn. A like arrangement is used in connection with the bar B' and tank F.

Without limiting myself to the precise construction and arrangement of parts shown, I claim—

1. The combination with a plurality of tanks, of a vertical shaft carrying a cross-head, and mounted to be revolved, and counterbalanced supporting-heads A A' suspended from said cross-head and movable into position over either of the tanks by the turning of said shaft, substantially as described.

2. The combination with a plurality of tanks, of a vertical shaft, a cross-head on said shaft, vertically-inovable supporting-heads A A' suspended from said cross-head and engaging said shaft to be guided thereby in their vertical movement, substantially as specified.

3. The combination with tanks F, G, of a shaft E, a cross-head carried by the shaft and provided with pulleys, cables passing over said pulleys to each of the supporting-heads, whereby each counterbalances the other while permitting vertical adjustment, substantially as set forth.

4. A supporting-head for supporting hanks or skeins for dyeing, &c., consisting of upper and lower cross-bars adjustably connected together, pins 1 journaled in the lower bar and projecting from opposite sides thereof, pins 2 journaled in the upper cross-bar and projecting from opposite sides thereof, a gear 3 on each of said pins 2 intermediate its ends, said gears meshing with each other, and means for rotating said gears, substantially as described.

5. The combination with a tank, of a head, as A, supported to have vertical movement relatively to the tank, skein-supporting pins carried by the upper and lower bars of the head, gearing connecting the pins in the upper head to each other and to a pinion, as 33, and a positively-driven pinion, as 35, supported adjacent to the tank to engage the pinion 33 when the head is lowered, substantially as described.

6. A mercerizing-machine provided with two tanks F G and two heads A A', means for supporting and stretching the hanks upon the heads, and means for connecting the heads to counterbalance each other and permit alternate vertical motion in different directions, substantially as set forth.

7. A mercerizing-machine provided with two tanks F G and two heads A A', each with skein carrying and stretching devices, and a support for the heads about which they may turn, and means for connecting the heads to counterbalance each other and permit alternate vertical motion in different directions, substantially as set forth.

In testimony whereof I have signed my name to this specification in the presence of two subscribing witnesses.

GEO. W. MILLER.
